UNITED STATES PATENT OFFICE.

ARTHUR C. ROWLEY, OF PHILADELPHIA, PENNSYLVANIA, ASSIGNOR TO ASSOCIATED AUTOMATIC SPRINKLER COMPANY, OF PHILADELPHIA, PENNSYLVANIA, A CORPORATION OF DELAWARE.

AUTOMATIC SPRINKLER.

1,231,653.

Specification of Letters Patent.

Patented July 3, 1917.

Application filed May 22, 1913. Serial No. 769,139.

To all whom it may concern:

Be it known that I, ARTHUR C. ROWLEY, a citizen of the United States, and a resident of the city of Philadelphia, county of Philadelphia, State of Pennsylvania, have invented certain new and useful Improvements in Automatic Sprinklers, of which the following is a specification, reference being had to the accompanying drawings.

10 The main objects of this invention are to provide an improved automatic sprinkler of simple and durable construction, which will be thrown into operation upon the rise in temperature to a predetermined degree; to provide an improved automatic sprinkler which will remain in operative position during long periods of time without being subject to corrosion or other injurious action tending to prevent the automatic action of the sprinkler at the predetermined temperature; to provide an improved sprinkler which will respond promptly to a predetermined temperature higher than the maximum normal atmospheric temperature, 25 but which will remain inoperative but always ready for action during practically indefinite periods of time under normal atmospheric conditions; to provide in an automatic sprinkler an improved valve and 30 means for retaining the same in position; to provide an improved fusible link or connection; and to provide other improvements as will appear hereinafter.

In the accompanying drawings, Figure 1 is a vertical central section, partly in side elevation, of an automatic sprinkler constructed in accordance with this invention; Fig. 2 is a rear elevation of the same; Fig. 3 is an enlarged perspective view of a fusible link or connection forming a part of the same; Fig. 4 is an enlarged section on line 4—4 of the said link; Figs. 5, 6, 7 and 8 are enlarged top plan views of parts of the said sprinkler; and Fig. 9 is an enlarged fragmentary section on line 9—9 of Fig. 2.

Referring to the drawings, one embodiment of this invention comprises a frame including a comparatively short tubular portion or nozzle 1 and a yoke 2 integral therewith, the frame being preferably arranged vertically and with the tubular portion projecting vertically downwardly from the

yoke and in vertical alignment therewith. The tubular portion 1 is open at both ends and is exteriorly threaded from its outer end for a portion of its length inwardly, as at 3, to adapt it to be connected to a suitable water supply pipe (not shown). The inner end of the tubular portion is interiorly cylindrical and forms a circular outlet 4 for the water from the supply pipe.

For holding the nozzle 1 normally closed a cap or valve 5 is provided to cover the inner end or outlet of the nozzle 1, and a circular washer 6 of copper or any other suitable material is interposed between the valve 5 and the inner end of the nozzle 1. The washer 6 is preferably composed of a flat annular marginal portion 7, and a central substantially flat circular depressed portion 8 which is connected to the marginal portion by an annular side wall 9 preferably a little less in external diameter than the diameter of the outlet 4, and which engages in the outlet 4 when the annular flat marginal portion of the washer is in engagement with the annular inner end of the nozzle 1. The annular side wall 9 of the washer preferably converges or tapers slightly downwardly so that only a very small portion of this side wall could be in contact with the internal wall of the nozzle when the washer is in operative position. The inner end of the nozzle is also externally tapered or chamfered inwardly so as to form a comparatively narrow circular edge or seat for the washer to bear against, thus insuring a water tight joint between the washer and the seat and minimizing the tendency of the washer to become bound to the seat by corrosion. If preferred, the central substantially flat circular depressed wall 8 of the washer may be omitted, and the washer would then consist only of the substantially flat annular marginal portion 7 and the converging annular side wall 9 surrounding a central circular opening, as shown in Fig. 8. By this construction of the washer and its seat, the ordinary tendency of corrosion between the washer and the nozzle 1 is reduced to a minimum, and all danger of the washer adhering to the nozzle so as to prevent the automatic operation of the sprinkler is practically eliminated.

The valve 5 is preferably circular in outline and is preferably provided upon its under side with a flat annular marginal surface and a coaxial circular annular projection 5' preferably slightly less in external diameter than the internal diameter of the annular side wall 9 of the washer 6 and preferably slightly less in thickness than the depth of the central depression in the washer. This annular projection holds the valve from lateral displacement with respect to the washer with the flat marginal annular portion of the under side of the valve in contact with the corresponding flat marginal annular surface of the washer.

For holding the valve 5 and the washer 6 normally clamped in position against the inner end of the nozzle 1, to keep the nozzle normally closed, there are two opposed levers or strut members 10 and 11, one arranged above and supported by the other. The lower lever, 10, is provided at its lower end with a downwardly projecting spur 12 substantially circular in transverse section and having a rounded or substantially semi-spherical convex under surface which engages against a correspondingly rounded concave wall 13 provided therefor and forming a central recess in a circular projection 14 or seat provided upon the upper side of the valve 5. The upper lever 11 is provided at its upper end with an upwardly projecting spur 15 substantially circular in transverse section and having a rounded convex upper surface which engages against a correspondingly rounded concave wall 16 of a central recess provided therefor in the lower end of a vertical screw 17, which is threaded through a hub 18 forming a part of the yoke 2, the screw being arranged in longitudinal alinement with the nozzle 1. The two levers 10 and 11 are arranged to fulcrum or swing upon each other, as at 20, about a horizontal axis extending transversely of the levers and closely adjacent but normally outside of the line of thrust and substantially midway between the screw 17 and the valve 5, the upper end of the lower lever being provided with a longitudinally horizontal groove 21 bounded by a wall substantially semi-cylindrical in transverse section, and the lower end of the upper lever being provided with a corresponding longitudinally straight and transversely convex rounded edge 22 arranged to engage against and to rock upon the semi-cylindrical concave wall 21 of the lower lever 10.

For holding the levers 10 and 11 in operative position, the levers are provided with laterally projecting arms 25 and 26 respectively, which diverge slightly outwardly when the levers are in operative position, and the outer ends of which are oppositely curved to form oppositely arranged hooks

27 and 28 respectively. One of the arms, in this instance the upper arm 26, is preferably provided with oppositely arranged comparatively short lateral projections 29 arranged to engage alternately against the opposite arms of the yoke 2 to prevent corrosion between the arms and the yoke.

For holding the levers 10 and 11 in position subject to being automatically released at a predetermined temperature, the free ends or hooks 27 and 28 of the levers are connected by a fusible link or coupling comprising two plates 35 and 36 which are constructed exactly alike, and which are arranged when in operation with one side of one plate in engagement with the corresponding opposite side of the other plate, and with the plates arranged longitudinally in reverse order. Each of these plates has a substantially flat body portion which is provided with an aperture 37 arranged between the center of the plate and one of its edges, and with a corresponding diametrically opposed marginal radial recess or slot 38, and each plate is provided with three small corrugations 39, 40 and 41 arranged in a row or series extending diametrically of the plate and transversely between the aperture 37 and the slot 38. These corrugations 39, 40 and 41 are formed between four parallel kerfs and are arranged so that the two outside corrugations project outwardly from one side of the body portion of the plate, and the intermediate corrugation projects outwardly from the other side of the body portion of the plate. Each plate is also provided with a plurality of comparatively short marginal crimps 45 arranged to form radial projections upon one side of the plate and corresponding recesses or depressions upon the other side of the plate, the crimps preferably terminating at their inner ends in oblique shoulders as shown in Fig. 9. The portion 46 of each plate between its aperture 37 and its marginal edge is crimped or bent inwardly, as shown in Fig. 3, to bring this portion in alinement with the plane dividing the body portions of the two plates, so that the line of stress between the two hooks 27 and 28 will be substantially coincident with the plane dividing the body portions of the two plates.

When in operative position, the two plates 35 and 36 are arranged inversely with respect to each other, with the aperture 37 of one plate in alinement with the slot 38 of the other plate and with one of the hooks 27 and 28 engaging in each aperture 37. As thus arranged, the projections formed by the crimps 45 of one plate engaging in the corresponding recesses formed by the crimps 45 of the other plate, and the intermediate corrugation 40 of one plate engages in the recess formed by the intermediate corrugation 40 of the other plate, and the two out-

side corrugations of the latter plate engage in the recesses formed by the corresponding outside corrugations of the other plate, the corrugations being arranged to form a continuous key-way. The two plates 35 and 36 are held together by means of a key 50 of fusible metal which is arranged in the recesses provided by the outside corrugations of one of the plates and the intermediate 10 corrugation of the other plate, as best shown in Figs. 3 and 4. This key is preferably formed in these recesses by clamping the two plates together between coöoperating parts recessed to form in combination with 15 the corrugations of the plates a suitable mold for the key and then pouring the fusible metal while in a molten state into the mold. For conveniently performing this operation, the two plates may be clamped between two 20 jaws of a pair of suitably constructed soldering and holding pliers which are arranged to form in combination with the plates a suitable mold for the key. By thus molding the pin or key as a unit in the recesses or the key-way provided therefor by 25 the corrugations of the plate, the key adheres to the plates and the plates are securely held together without the possibility of any looseness or play between the plates 30 and a maximum efficiency of the key is thus obtained. If found desirable, the substantially flat body portions, and also the crimped portions of the two plates, may also be soldered or "sweated" together by a fusible 35 metal, although it is thought that the plates will be sufficiently secured together merely by the key.

For deflecting and spreading the water after it issues from the nozzle 1, there is provided a sprinkler cup or spreader 51, which may be of any suitable shape and which is rigidly secured by riveting or otherwise to the upper end of the screw 17. This spreader 51 also serves as a convenient hand 45 wheel for adjusting the screw 17.

To provide a slight amount of yielding resilient action between the valve 5 and the levers 10 and 11, the valve 5 and its projection 14 may be made, as shown in Figs. 50 1, 5 and 6, of two separate parts, the valve 5 being comparatively rigid and provided upon its upper side with a circular coaxial recess 52 and a central projection 52', and the projection 14 being made of brass or 55 other resilient material and being provided with a flat circular base 53 adapted to fit snugly in the recess of the valve and having upon its under side a central recess 54 to permit of a slight yielding of the central 60 portion of the projection under the pressure of the lever 10 in engagement therewith, the projection 52' on the valve being intended to limit the yielding of the projection 14. The base 53 of this projection may be com- 65 pressed or expanded into the recess 52 of

the valve so as to hold the projection bound or connected to the valve, or the projection may be snugly but removably seated in the recess in the valve and held in place by the pressure of the lever 10. 70

In the operation of an automatic sprinkler constructed in accordance with this invention, the key 50 of fusible metal which secures the two plates of the link together coöperates with the corrugations 39, 40 and 41, and crimps 45, and effectively prevents, under ordinary atmospheric conditions the "creeping" of the plates 35 and 36 longitudinally with respect to each other, or other movement of the plates with respect 80 to each other, sufficient to release the valve or to cause leakage at the nozzle. In some of the automatic sprinklers heretofore constructed, it has been found that when a valve is held closed by two parts connected by fusible metal, unless some provision is made to prevent "creeping" of the parts under ordinary atmospheric conditions, there is a liability of having the valve prematurely released or opened, resulting frequently 85 in considerable unnecessary damage being done by the premature discharge of water. In the present invention, the valve is held tightly closed for indefinite periods under ordinary atmospheric conditions, and until 90 the predetermined critical temperature is reached. When the critical temperature is reached, as in the case of a fire the fusible key 50 instantly melts, and also, simultaneously, any other fusible connection, which may be 95 between the plates 35 and 36, melts, and the plates are then moved longitudinally in opposite directions under the opposed actions 100 of the two levers 10 and 11 and, during this longitudinal movement, the inclined 105 walls of the corrugations 39, 40, and 41 of the plates act to separate the plates laterally and to prevent their being reunited by the cooling action of the released water upon 110 the melted fusible metal. The separation of the plates 35 and 36, by the melting of the fusible metal, permits the water to force the valve 5 and the levers 10 and 11 out of position and the water is then discharged against the spreader 51 and effectually distributed. 115

Although only a single form has been shown in which this invention may be embodied, it is to be understood that the invention is not limited to any specific construction but might be applied in various constructions and adapted to various purposes. 120

Having thus fully described my invention, I claim and desire to protect by Letters Patent of the United States:

1. A fusible link comprising two plates, each of said plates being provided with a corrugation projecting into a corresponding recess provided therefor in the other 130

plate, and said corrugations being arranged to form a continuous key-way, and a key of fusible material arranged in said key way.

2. A fusible link comprising two plates, each of said plates being provided with a corrugation substantially V-shaped in cross section projecting into a corresponding recess provided therefor in the other plate and said corrugations being arranged to 5 form a continuous key-way, and a key of fusible material arranged in said key-way.
3. A fusible link comprising two plates, each of said plates being provided with a corrugation projecting outwardly from one 15 side of said plate, and with an adjacent corrugation projecting outwardly from the other side of said plate, and one of said corrugations of each plate engaging in a recess formed by one of said corrugations of 20 the other plate and said corrugations being arranged to form a continuous key-way, and a key of fusible metal arranged in said key-way.

4. A fusible link comprising two plates, each of said plates being provided with a corrugation projecting outwardly from one side of said plate, and with an adjacent corrugation projecting outwardly from the other side of said plate, and one of said 25 corrugations of each plate engaging in a recess formed by one of said corrugations of the other plate, and said corrugations being arranged to form a continuous key-way, and a key arranged in said key-way and 30 fusibly connected to each of said plates.

5. A fusible link comprising two members providing a key-way, and a key in said key-way and fusibly connected to each of said members, one of said members being 40 provided with a plurality of marginal spaced projections arranged to engage in openings provided therefor in the other member.

6. A fusible link comprising two members providing a key-way, and a key in said key-way, and fusibly connected to each of said members, each of said members being provided with a marginal crimp and the marginal crimp of one of said members being 45 arranged to engage in the marginal crimp of the other of said members to hold said members in a predetermined relationship.

7. A fusible link comprising two plates and fusible means connecting said plates, each of said plates comprising a substantially flat body portion, provided with a plurality of marginal crimps radiating from the central portion of said plate, and the crimps of one of said plates being arranged 55 to engage respectively the crimps of the other of said plates.

8. A fusible link comprising two plates, each of said plates being provided with a corrugation projecting into a corresponding 60 recess provided therefor in the other plate,

and said corrugations being arranged to form a continuous key-way, and each of said plates being provided with a plurality of marginal crimps, and the said marginal crimps of one of said plates being arranged 70 to engage respectively the said marginal crimps of the other of said plates, and a key of fusible material arranged in said key-way.

9. A fusible link comprising two plates, each of said plates being provided with a corrugation projecting into a corresponding recess provided therefor in the other plate, and said corrugations being arranged to 75 form a continuous key-way, and each of said 80 plates being provided with a plurality of marginal crimps radiating from the central portion thereof, and the said marginal crimps of one of said plates being arranged to engage respectively the said marginal 85 crimps of the other of said plates, and a key of fusible material arranged in said key-way.

10. A fusible link comprising two plates, each of which is provided with an aperture 90 and a diametrically opposed marginal slot, the aperture of each plate being arranged to register with the slot of the other plate, and fusible means connecting said plates, the portion of each plate between its aperture 95 and its marginal edge being crimped inwardly to form a bearing.

11. A fusible link comprising two plates, each of which is provided with an aperture and a diametrically opposed marginal slot, 100 the aperture of each plate being arranged to register with the slot of the other plate, and fusible means connecting said plates, the portion of each plate between its aperture and its marginal edge being crimped inwardly approximately along a radius of 105 said plate to form a bearing.

12. A fusible link comprising two plates, each of which is provided with an aperture and a diametrically opposed marginal slot, 110 the aperture of each plate being arranged to register with the slot of the other plate, and fusible means connecting said plates, the portion of each plate between its aperture and its marginal edge being crimped inwardly approximately along a radius of 115 said plate to form a bearing, and said bearings being approximately in a line extending diametrically of said fusible link and approximately midway between the opposite sides 120 thereof.

13. A fusible link comprising two plates, each of which is provided with a series of three corrugations including two spaced corrugations integral with and projecting outwardly from one side of each plate and forming corresponding spaced recesses upon the other side of each plate and an intermediate corrugation integral with and projecting outwardly from the other side of each 125 plate.

plate and forming a corresponding intermediate recess on the first said mentioned side of each plate, and the said spaced corrugations of one plate engaging in the said spaced recesses of the other plate, and the said intermediate corrugations on the latter plate engaging in the said intermediate recesses on the other plate, said corrugations forming a continuous key-way, and a key of fusible material in said key-way.

14. A fusible link consisting of a plurality of intermeshing elements; and a bar of relatively fusible material extending through the intermeshing portions of said elements to lock them together.

15. A fusible link consisting of a plurality of elements, of which at least one is provided with a portion projecting into the other; with a body of relatively fusible material extending into said projecting portion to lock it to the second element.

16. A fusible link consisting of a plurality of plates each having at least one projecting portion extending into another plate; with a body of relatively fusible material extending through said projecting portions to lock the elements together.

17. A fusible link consisting of a plurality of elements, of which at least one is provided with a bent out strip extending into

another plate; with a body of fusible material extending through the passage between the strip and the body of the adjacent element to lock together said elements.

18. A fusible link consisting of a plurality of elements, each having a plurality of bent out strip portions; with a bar of fusible material extending through the channels formed by said bent out strip portions to lock the elements together. 35

19. A fusible link consisting of a plurality of plates each having two series of bent out strip portions respectively projecting in opposite directions and intermeshing with those of the other elements; with a body of relatively fusible material extending through said intermeshing strip portions to lock the elements together. 40

20. A fusible link consisting of a plurality of intermeshing elements; and a body of 50 relatively fusible material connecting the adjacent faces of said elements and extending through their intermeshing portions to lock them together.

In witness whereof, I have hereunto set 55
my hand this 20th day of May, A. D., 1913.

ARTHUR C. ROWLEY.
